UNITED STATES PATENT OFFICE.

JAMES GURNEY WALLACE, OF BALTIMORE, MARYLAND, ASSIGNOR OF ONE-HALF TO
ANDREW R. KECKLER, OF BALTIMORE, MARYLAND.

WATER-TIGHT CONTAINER.

Application filed October 24, 1923. Serial No. 670,521.

To all whom it may concern:

Be it known that JAMES G. WALLACE, a citizen of the United States of America, residing at Baltimore, in the State of Maryland, has invented new and useful Improvements in Water-Tight Containers, of which the following is a specification.

At resort and other bathing beaches, the male bathers frequently carry cigarettes, 10 cigars or tobacco with them while in bathing and while they are actually in the water they resort to hiding their cigarettes, cigars or tobacco and when they leave the water to lie on the beach, they recover their smokes. 15 Sometimes the smokes are stolen or ruined due to the dampness of the sand or some one splashing water on them or the matches go bad from the dampness and in this way they are more or less inconvenienced.

20 In view of this, the present invention has for its purpose to provide a water-tight container for the purpose of preserving the smokes against the dampness and allowing the bather to carry the smokes in a fold in the bathing suit or on a string around the 25 wrist or one which hangs from the neck. The container may also carry the matches, it being possible to open the container above the surface of the water while in the water, 30 removing the cigarette or other smoke or removing the tobacco or cigar, thereby permitting the bather to smoke either while in the water or lying on the beach.

Another purpose is to provide a water-tight container, the construction and arrangement of which are such as to permit the container to be inflated, with the contents therein, thereby indicating whether or not moisture has seeped through the container while in the water.

35 Female bathers very often remain out of the water simply to display their bathing costumes and mainly to prevent their complexions from being destroyed. Therefore, 40 the present invention may be used for carrying vanity cases, preserving them from moisture, and allowing the female bather, after leaving the water, to restore her made-up complexion.

45 The container may also be used to carry a time-piece in order to permit the bather to be informed as to the length of time spent in bathing and thereby prevent overtime in the water.

50 A further purpose is to provide means

for closing the opening to the container which is constructed of any suitable water-proof material, such as rubber, rubberized fabric or the like, together with a cord or tie string, in connection with means for preventing the string or cord from cutting the material of the container while in a tightened position about the neck of the container.

55 A still further purpose is the provision of a porous spongy filler, preferably of rubber or the like, insertable in the open end of the container and capable of being compressed tightly when the tie cord or string is drawn tightly about the neck end of the container, thereby precluding moisture.

60 Also, the invention aims to provide means for attaching said filler and the tie string or cord to the container to prevent loss thereof.

65 It is to be understood that the particulars herein given are in no way limitative and that, while still keeping within the scope of the invention, any desired modifications of detail and desired proportions may be made in the device according to the circumstances.

70 The invention comprises further features and combinations of parts to be hereinafter set forth, shown in the drawings and claimed.

75 In the drawings:

Figure 1 is a view in perspective of the improved container constructed in accordance with the invention, showing the open end closed, the same containing a package of cigarettes or several supplies of tobacco 80 including a small pipe or cigars and matches or a time-piece.

85 Figure 2 is a vertical sectional view showing the container with cigarettes and matches as contents.

90 Figure 3 is a perspective view of the container with its end open, with the tie string or cord and the filler suspended in position ready for use.

95 Referring to the drawings, 1 designates a 100 flexible container which may be any size or shape and constructed of any suitable yieldable or pliable water-proof material, preferably rubber or rubberized fabric or the like. The closed end of the container has a stiffened portion 2 upon which a package of cigarettes, vanity case or the like may rest, while the open end of the container is large enough to permit of the insertion of a package of cigarettes, tobacco, 105 110

pipe and matches or cigars, if the container is made large enough to hold cigars.

Secured on the exterior of the container is a strap 3 which is adjacent the open end 5 of the container. The central portion of the strap is spaced from the container to permit of the reception of a tie cord or string 4. In fact, the tie cord or string may be tied to the strap so as to prevent its loss.

- 10 Also, a rubber connector 5 is secured to the strap 3 and to a filler 6 which is constructed of any suitable compressible porous or spongy material, such as rubber or the like, and which is insertable in the open end 15 of the container so that when the open end is drawn tightly about the filler, the filler compresses, closing the pores of the material and thereby precluding entrance of moisture and air.
- 20 The opposite ends of the tie cord or string 4 constructed of any suitable material pass through perforations 6^a of a button 7 constructed of any suitable fibrous material, such as leather, used for preventing the cord 25 or string from cutting the material of which the container is constructed.

The contents to be carried in the container are first placed therein and the porous spongy filler is then inserted in the open end 30 of the container, after which the container may be inflated by blowing through the pores of the filler. When the container is distended or inflated sufficiently, the tie cord or string, having been first partially tied, 35 is drawn tight, hugging or shirring the wall of the container about the filler, crushing or compressing the filler in such a manner as to close all the pores thereof and thereby preclude the escape of air. The tie cord or string is then further tied in a bow knot, as 40 illustrated in Figure 1, and in this condition the container may be carried in the water when bathing. The container is inflated

just sufficiently to distend the walls thereof away from the contents and as long as the 45 container remains inflated, it will indicate that moisture has not reached and damaged the contents. By simply pulling the bow knot and then by pulling first one and then the other end of the cord, the partial tie 50 may be loosened, allowing the open end of the container to open and permit access to the contents. The extremities of the cord or string are provided with knots 8 to prevent detaching the cord or string from the 55 fiber button.

The invention having been set forth, what is claimed is:

1. An inflatable container having one end open and including a porous compressible filler within the open end, and means for shirring the wall of the container around the filler and compressing the filler and thereby precluding entrance of moisture from the contents of the container.
2. A water-tight container having an open end, a porous compressible filler engaged within the open end, and means carried by the container for drawing the wall of the container tightly about the filler in such 70 wise as to preclude entrance of moisture.
3. In a device as specified, the combination with a fluid-tight container having an open end, of a porous compressible filler carried by the container and insertable in said open end, a tie member engaged about and adapted to draw the wall of the container about and compress the filler, thereby precluding entrance of moisture, and means carried by and cooperating with the tie member to prevent the tie member from cutting the wall of the container when drawn tight.

In testimony whereof he affixes his signature.

JAMES GURNEY WALLACE.
